CLAIM

The ornamental design for a case for electronic device, as shown and described.

DESCRIPTION

FIG. 1 is a front perspective view of a case for electronic device, having inner portion and outer portion, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded front perspective view thereof showing the inner and outer portions of the case for electronic device separated for clarity of disclosure;

FIG. 10 is an exploded rear perspective view thereof;

FIG. 11 is a front perspective view showing only the inner portion of the case for electronic device for clarity of disclosure;

FIG. 12 is a rear perspective view thereof;

FIG. 13 is a front perspective view showing only the outer portion of the case for electronic device for clarity of disclosure; and,

FIG. 14 is a rear perspective view thereof.

The dashed broken lines in the drawings depict portions of the case for electronic device that form no part of the claim. The dash-dot broken lines define boundaries of the claim that form no part of the claim.

1 Claim, 14 Drawing Sheets
